UNITED STATES PATENT OFFICE

153,336

DESIGN FOR AN ELECTRIC IRON

Loy C. Carter, Radford, Va.

Application April 1, 1947, Serial No. 138,100

Term of patent 14 years

(Cl. D49—6)

To all whom it may concern:

Be it known that I, Loy C. Carter, a citizen of the United States of America, residing at Radford, county of Montgomery, and State of Virginia, have invented a new, original, and ornamental Design for an Electric Iron, of which the following is a specification, reference being had to the accompanying drawing, forming a part thereof, wherein:

Figure 1 is a view in side elevation of an electric iron, showing my new design;

Figure 2 is a top plan view of the electric iron.

Figure 3 is a view in rear elevation of the electric iron, and

Figure 4 is a view in front elevation of the electric iron.

I claim:

The ornamental design for an electric iron, substantially as shown.

LOY C. CARTER.
